AUXILIARY FUEL-ATOMIZER FOR INTERNAL COMBUSTION ENGINES

John E. Gombos, Elizabeth, N. J., assignor of
one-half to Egbert Stockert, Vienna, AustriaApplication September 19, 1934, Serial No. 744,720
In Hungary September 19, 1933

10 Claims. (Cl. 123—122)

This invention relates to improvements in atomizing devices for use in conjunction with internal combustion engines, and has for its object to permit of the attainment of practically perfect combustion of a very wide range of fuels including those of high boiling point, with the usual types of carburetor, and at all speeds of the engine, without the necessity for alterations in or special adjustment of the carburetor. For this purpose, the present invention provides a novel type of unit for interposition between the engine and the carburetor comprising an intake manifold of special construction and in combination therewith, and with the exhaust system of the engine, a fuel atomizing and mixture pre-heating device of particular construction to be detailed in due course.

As is well known, the majority of auxiliary atomizers for heavy fuels for use with internal combustion engines only begin to supply a combustible mixture after the attainment of a certain speed of the engine, so that in starting and during slow running of the engine the less volatile particles of the fuel pass into the cylinders in a non-atomized state, with the result that the combustion is imperfect, smoke and soot formation is set up, and the engine loses efficiency and runs uneconomically. It has also been proposed to heat the induction pipe of internal combustion engines with a view to assisting the vaporization and combustion of heavy fuels. The devices hitherto proposed for this purpose, however, suffer from the drawback that they are apt to produce an overheated fuel-air mixture which, on entering the relatively cooler engine, becomes to some extent condensed and thus likewise leads to imperfect combustion and uneconomical running.

The device according to the present invention obviates the above-mentioned drawbacks and consists essentially in an atomizing chamber interposed between the carburetor and the induction pipe of the engine and provided with heating means for the maintenance of a suitable temperature during starting and slow running of the engine. The invention further provides for the automatic discontinuance of the said heating at the required moment and for the subsequent heating of the atomizing chamber by means of the combustion gases from the exhaust of the engine.

A form of construction embodying the invention is shown by way of example in the accompanying drawing, in which:

Fig. 1 shows the entire device in horizontal 55 longitudinal section.

Fig. 2 is a transverse section of the combined manifold.

Referring to Fig. 1, the device consists of the induction pipe 8 having adjoining it in a midway position the flanged tube 1. Within the tube 1 there is arranged the atomizing chamber 2 which on its inner surface may be provided with the electric heating element 3a, 3b. This heating element 3a, 3b is connected by means of the conductors 3¹, 3² to the source of current 3. Apart from the electric heating element 3a, 3b, and separated therefrom by a partition, there is also provided in the atomizing chamber 2 a system of propeller blades 5 adapted to rotate about a shaft 4. The device according to the invention further comprises an annular chamber or jacket 10 which surrounds at least part of the atomizing chamber, and which communicates with the exhaust pipe 9 by means of the pipes 10 and 10a, and on the other hand with the outside atmosphere by means of the discharge pipe 10c. This system of pipes 10, 10a, and 10c thus constitutes, together with the annular chamber or jacket 10b, a by-pass from the exhaust pipe of the engine for the heating of the atomizing chamber by means of the hot exhaust gases.

In the induction pipe 8 there may be further arranged a plate 6a which is provided with perforations 6b, and of which the portion extending into the tube 1 forms with the latter the annular space 1, 1a. On the outside of the exhaust manifold 9 there may be provided the cooling and heat-distributing ribs 11a, 11b, 11c, 11e (Fig. 2). Finally, between the exhaust manifold 9 and the induction pipe 8 there may be provided an air cooling space 12 communicating with the outside atmosphere (see Figs. 1 and 2).

The suction of the engine draws the fuel-air mixture from the carburetor in the direction of the arrow 1a into the atomizing chamber which is suitably heated by the electric heating element 3a, 3b connected into circuit with the source of current 3 on the starting of the engine. The fuel particles in the mixture are further broken up by the action of the rotating propeller system which is rotated by the suction of the engine, and at the same time flung thereby against the partition covering the heating element 3a, 3b. The fuel thus becomes extremely finely atomized and thoroughly commixed with the air, and the mixture thus produced passes on into the induction pipe 8.

As soon as the engine has attained a certain speed the heating element is cut off from the

source of current 3, whereupon the heating jacket 10b is brought into action. The hot waste gases pass from the exhaust manifold through the by-pass pipes 10 and 10a into the annular chamber 10b where they give up their heat to the atomizing chamber 2, to promote the atomization of the fuel after the auxiliary electric heater has been cut off. The by-pass pipes 10 are disposed parallel with and in close proximity to the portions 10 of the induction pipe 8 furthest removed from the heated atomizing chamber 2, so that any non-vaporized fuel happening to be carried along by the mixture into the induction pipe 8 becomes effectually vaporized in the latter in consequence 15 of the heat transmitted thereto from the by-pass pipes 10 traversed by the hot exhaust gases. The particles of fuel passing unvaporized into the induction pipe and condensing therein when the engine is cold or running slow pass through 20 the perforations 6b in the plate 6a into the annular chamber 1, 1a where they are vaporized by the heat from the chamber 10b and returned in a gaseous state into the induction pipes as a fuel reserve. The by-passed exhaust gases, after having fulfilled their purpose in assisting the atomization of the fuel, escape into the open by way of the discharge pipe 10c.

The actual construction of the auxiliary atomizing device according to the present invention 30 can be modified to any extent without departing from the spirit and scope of the invention, the construction here described and illustrated being intended merely to serve as an example. So, for instance, when highly volatile fuels are used 35 such as gasoline, or benzine, the electrical heating means may be dispensed with and also the baffle plates, the main purpose of the invention being to maintain the fuel charge at the constant temperature until it enters into the engine cylinders. This purpose is accomplished as indicated 40 in the specification by circulating the exhaust gases around the atomizing chamber and by arranging the by-pass pipe as well as the discharge pipe alongside and parallel to the intake manifold 45 so that there is a heat exchange relationship between the two.

The new device according to the invention can be constructed either as a small unit for 50 interposition between the carburetor and the induction pipe of the engine, or, more particularly for use with engines having the induction pipe and the exhaust manifold on the same side of the engine, as a larger unit comprising exhaust manifold, intake manifold, and atomizing device proper.

I claim:

1. In an internal combustion engine an intake manifold, an exhaust manifold at least partly 60 surrounding the said intake manifold, a tubular casing adjoining the said intake manifold, atomizing means in the said casing, a jacket surrounding the said chamber at least in part, a by-pass pipe from the said exhaust manifold and communicating with the said jacket, and a discharge pipe connected to the said jacket and communicating with the outside atmosphere, the said by-pass pipe and discharge pipe being enlarged in diameter for at least a portion of their length 65 and disposed alongside and in close proximity to the said intake manifold.

2. In an internal combustion engine an intake manifold, an exhaust manifold at least partly 70 surrounding the said intake manifold, a tubular casing adjoining the said intake manifold, atom-

izing means in the said casing, a jacket surrounding the said chamber at least in part, a by-pass pipe from the said exhaust manifold and communicating with the said jacket, a discharge pipe connected to the said jacket and communicating with the outside atmosphere, a baffle plate disposed substantially parallel to the side of the said induction pipe nearest the said chamber and extending into the annular space between the said chamber and tubular casing as far as the said jacket, and perforations in the said baffle plate, the said by-pass pipe and the said discharge pipe being enlarged in diameter for at least a portion of their length and disposed alongside and in close proximity to the said intake manifold. 15

3. The combination with the intake and exhaust manifold of an internal combustion engine; of an auxiliary fuel atomizer comprising a tubular casing adapted to be connected to said intake manifold, means forming an atomizing chamber within said casing and spaced from the walls thereof whereby an annular space communicating direct with said intake manifold is formed, means for preliminary heating the fuel charge in said chamber, comprising a jacket partly occupying said annular space and a by-pass pipe connecting said jacket with said exhaust manifold, and secondary heating means comprising baffle plates for receiving the non-vaporized portion of the fuel charge within said intake manifold and extending into said annular space to said heating jacket, whereby complete vaporization is obtained. 20

4. The combination with the intake and exhaust manifolds of an internal combustion engine and a source of electric current; of an auxiliary fuel atomizer comprising a tubular casing adapted to be connected to said intake manifold, means forming an atomizing chamber within said casing, means for preliminary heating the charge in said chamber, comprising laterally disposed electric heating elements in said chamber adapted to be connected to said source of electric current whereby said fuel charge is partly vaporized, and secondary heating means at least partly within said intake manifold, whereby complete vaporization is obtained. 35

5. The combination with the intake and exhaust manifolds of an internal combustion engine and a source of electric current; of an auxiliary fuel atomizer comprising a tubular casing adapted to be connected to said intake manifold, means forming an atomizing chamber within said casing and spaced from the walls thereof whereby an annular space communicating direct with said intake manifold is formed, means for preliminary heating the fuel charge in said chamber, comprising laterally disposed heating elements in said chamber adapted to be connected to said source of electric current, a jacket partly occupying said annular space and a by-pass pipe connecting said jacket with said exhaust manifold, and secondary heating means comprising baffle plates for receiving the non-vaporized portion of the fuel charge within said intake manifold and extending into said annular space to said heating jacket, whereby complete vaporization is obtained. 50

6. A fuel vaporizer for internal combustion engines of the type having an intake manifold, an exhaust manifold and a carburetor comprising a casing positioned intermediate the intake manifold and the carburetor, an atomizing chamber in said casing communicating with the carburetor and the intake manifold, a heating jacket 65

at least partly surrounding said atomizing chamber, means for circulating the exhaust gases in said heating jacket, said means being disposed alongside of at least a portion of the intake manifold and in near proximity thereof whereby uniform temperature of the vaporizing fuel charge is obtained and condensation prevented in said intake manifold.

5. The combination with the intake manifold and the exhaust manifold of an internal combustion engine; of a fuel vaporizer comprising a casing adapted to be connected to said intake manifold and to the carburetor of the engine, an atomizing chamber within said casing communicating with the carburetor and the intake manifold, a heating jacket at least partly surrounding said atomizing chamber, means for circulating the exhaust gases in said heating jacket, said means comprising a by-pass pipe from said 10 exhaust manifold and a discharge pipe communicating with the outside atmosphere, said by-pass pipe and said discharge pipe being disposed alongside of said intake manifold and in near proximity thereof, whereby uniform temperature 15 of the vaporizing fuel charge is obtained and condensation prevented in said intake manifold.

6. The combination with an intake manifold, an exhaust manifold and a carburetor of an internal combustion engine; of a fuel vaporizer comprising a casing connected intermediate said intake manifold and said carburetor, an atomizing chamber within said casing communicating with the carburetor and the intake manifold, a heating jacket at least partly surrounding said 20 atomizing chamber, means for circulating the exhaust gases in said heating jacket, said means being disposed in heat exchange relationship with said intake manifold and baffle plates positioned in heat exchange relationship with said heating jacket, said baffle plates extending within said intake manifold substantially parallel to the walls thereof.

9. The combination with an intake manifold, an exhaust manifold and a carburetor of an internal combustion engine; of a fuel vaporizer comprising a casing connected intermediate said intake manifold and said carburetor, an atomizing chamber in said casing communicating with the carburetor and the intake manifold, a heating jacket at least partly surrounding said atomizing chamber, means for circulating the exhaust gases in said heating jacket, said means comprising a by-pass pipe from said exhaust manifold and a discharge pipe communicating with the outside atmosphere, said by-pass pipe and said discharge pipe being disposed alongside and in close proximity to said intake manifold at 25 least for a portion of its length, baffle plates positioned in heat exchange relationship with said heating jacket and extending within said intake manifold substantially parallel to the walls thereof.

10. In an internal combustion engine, means forming an atomizing chamber, a heating element situated within said chamber for the preliminary heating of the air-gas mixture, an exhaust pipe and a jacket situated adjacent said 25 atomizing chamber in heat-conducting relationship thereto, said jacket being adapted to be connected with said exhaust pipe to transmit exhaust gases passing therethrough, the heat of the exhaust gases being transmitted to said 30 atomizing chamber to heat the air-gas mixture after the interruption of said preliminary heating, another chamber adjacent said jacket and in heat-conducting relationship thereto, and means connected with the last-mentioned chamber for collecting unvaporized fuel particles and for transmitting them to the last-mentioned chamber, said fuel particles being vaporized by the heat transmitted to the last-mentioned chamber from said jacket.
